UNITED STATES PATENT OFFICE.

FELIX CANNON, OF HAMLET, NORTH CAROLINA.

LOCOMOTIVE DRIVING BOX.

Application filed November 6, 1924. Serial No. 743 262.

This invention relates to locomotive driving boxes and is an improvement over the construction shown in my prior Patent No. 1,384,381, granted July 12, 1921.

5 An object of the invention is the provision of a driving box employing a three quarter bearing brass which may be removed without dropping the wheels of the locomotive.

10 A further object of the invention is the provision of a driving box in which the bearing brass may be provided with a liner after the brass has reduced in size to the service.

15 A further object of the invention is the provision of means for locking the saddle in place.

In the accompanying drawings, I have shown one embodiment of the invention. In 20 this showing:

Figure 1 is an end elevation of a driving box showing the use of a three quarter bearing brass formed in two sections,

25 Figure 2 is a vertical sectional view on line 2—2 of Figure 1,

Figure 3 is a vertical sectional view on line 3—3 of Figure 2,

Figure 4 is a horizontal sectional view on line 4—4 of Figure 3,

30 Figure 5 is a view similar to Figure 1 showing a liner arranged between the driving box and the bearing brass,

Figure 6 is a perspective view of the bearing brass removed,

35 Figure 7 is a perspective view of the driving box removed from the locomotive frame,

Figure 8 is a similar view of the saddle, and,

Figure 9 is a perspective view of the liner 40 employed when the bearing brass becomes reduced in cross section.

Referring to the drawings, the reference numeral 1 designates a locomotive side frame provided with the usual pedestals 2 for the 45 reception of a driving box 3. As shown, the sides of the driving box are provided with grooves 4 to receive the pedestal and the driving box is retained in position by means of the usual pedestal brace 5. The 50 driving box is provided with the usual bearing receiving aperture 6 and is closed at the top as indicated at 7. The bottom portion of the driving box is open and is adapted to receive a saddle 8. As shown, 55 the side walls of the opening are provided with tapering grooves 9 adapted to receive

ribs 10, formed on the sides of the saddle, whereby the saddle will be moved upwardly toward the aperture 6, as it is placed in the driving box. The front of the driving box 60 is provided with a pair of bolts 11, which are adapted to be received in openings 12, formed in flanges 13 on the front of the saddle, which flanges are arranged in front of the driving box when the parts are in assembled position. As shown, these flanges are provided with projecting ends 14, adapted to engage the sides of the driving box (see Figure 4) and the saddle is retained in position by means of nuts 15. The saddle is provided 70 with a rear wall 16, the upper edge of which is curved on a radius substantially the same as the bearing aperture 6 of the driving box and a lubricating well 17 is formed therein. Suitable means are provided for locking the saddle in position independent of the nuts 75 11 and bolts 15. As shown, the front of the saddle is provided with a depending flange 18. This flange is provided with an opening 19. A locking plate 20 is adapted 80 to be arranged in front of this flange and the locking plate is provided with an opening adapted to receive a bolt or set screw 21 by means of which the locking plate is secured to the saddle. The saddle is provided 85 with a pair of vertical grooves 22, adapted to receive the edges of the locking plate and the upper edge of this plate is provided with a curved portion 23, curved on substantially the same radius as the 90 radius of the aperture 6. As shown, the plate 20 forms the front wall of the lubricant well 17 when the parts are assembled (see Figure 4). A bearing brass consisting 95 of a pair of sections 24 is adapted to be arranged in the driving box in the usual manner. The lower edge of each plate is adapted to engage the upper edge of the saddle, as shown in Figure 3 of the drawings, to retain them in proper position. As shown, 100 the rear wall of the aperture is provided with a flange 25 (see Figure 7) to prevent longitudinal displacement of the bearing brass. In Figure 6 of the drawings, I have shown a spacing member 26 which is adapted 105 to be inserted between the two sections of the bearing brass when the bearing brass becomes worn, to spread them, and thus take up wear. In Figure 5 of the drawings, I have shown a shim or liner 27 arranged in 110 the driving box between the wall of the aperture and the bearing brass to take up

wear when the amount of wear is so great that the spacer 26 will not suffice for this purpose.

The operation of the device will be apparent from the foregoing description. As the bearing brass wears, a spacer 26 is first inserted and a shim or liner 27 inserted upon further wear of the brass. The saddle may be adjusted upwardly by moving it toward the rear of the driving box, causing the ribs 10 to move upwardly in the tapered grooves 9. The construction is so simple and by providing the open portion of the aperture at the bottom, the brass may be removed without dropping the wheels of the locomotive.

It is to be understood that the form of my invention herewith shown and described is to be taken as a preferred example of the same, and that various changes in the shape, size, and arrangement of parts may be resorted to without departing from the spirit of the invention or the scope of the subjoined claims.

I claim:

1. A locomotive driving box having a smooth arcuate bearing receiving aperture, and having an opening beneath and communicating with said aperture, each of the side walls of said opening being provided with an inwardly projecting shoulder, a hollow saddle arranged in said opening and having portions slidably engaging said shoulder, a brass conforming in shape to and arranged in said aperture and having its lower edges contacting with said saddle, said saddle being provided at its front portion with flanges adapted to overlie the face of said driving box and being further provided inwardly of said flanges with vertical grooves, and a plate slidable in said grooves and forming a

closure for the front portion of said saddle.

2. A locomotive driving box having a tapered bearing receiving aperture, and having an opening beneath and communicating with said aperture, a brass formed of complementary members tapered similarly to and adapted to be received in said aperture, and a saddle arranged in said opening and having portions adapted to contact with the lower edges of said brass, said driving box being provided with supporting means for said saddle.

3. A locomotive driving box having a tapered bearing receiving aperture and having an opening beneath and communicating with said aperture, each of the side walls of said opening being provided with an inclined inwardly projecting shoulder, an arcuate brass formed of a pair of complementary members tapered similarly to and adapted to be received in said aperture, the lower edges of said brass being arranged below the center of curvature thereof, a saddle arranged in said opening and having portions projecting outwardly of said driving box, the lower edges of said brasses being adapted to contact with portions of said saddle, and means connected between said driving box and the projecting portions of said saddle for drawing the latter inwardly, said saddle having portions adapted to slide upon said shoulders to move said saddle upwardly as it is drawn inwardly.

4. A device constructed in accordance with claim 3 wherein the contacting portions of said brass and said saddle are arranged substantially radially of said brass.

In testimony whereof, I affix my signature.

FELIX CANNON.
